LIFTING JACK

Filed Aug. 18, 1924

G. Steele Inventor

John W. L.

Attorneys

UNITED STATES PATENT OFFICE.

GEORGE STEELE, OF DENVER, COLORADO.

LIFTING JACK.

Application filed August 18, 1924. Serial No. 732,858.

To all whom it may concern:

Be it known that I, GEORGE STEELE, a citizen of the United States, residing at Denver, in the county of Denver and State of Colorado, have invented a new and useful Lifting Jack, of which the following is a specification.

The present invention relates to lifting jacks, the primary object of the invention being to provide a jack of a novel telescoping construction including a plurality of moving parts, and a plurality of ratcheted parts, thereby increasing the lifting ratio of the jack and consequently increasing the lifting capacity of the jack over the jacks now in use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a longitudinal sectional view through a jack constructed in accordance with the present invention and showing the location of the pawls prior to their first movements in lifting.

Figure 2 is a longitudinal sectional view disclosing the locations of the pawls at the end of one stroke of the operating lever.

Figure 3 is a sectional view taken on line 3—3 of Figure 1.

Referring to the drawing in detail, the jack includes a base indicated at 5 which may be of any desired construction. Formed integral with the base and extending upwardly therefrom, is a hollow support 6 formed with a plurality of teeth 7 and arranged along one wall thereof.

Positioned in the hollow support 6 and adapted to operate therethrough, is a lifting post 8 which is also formed with teeth 9 extending throughout the length thereof, the teeth 9 being disposed in a direction opposite to the teeth 7 formed exteriorly of the hollow support for purposes to be herein-after more fully described.

The lifting post 8 is supplied with a head 10 to be positioned under an article to be

lifted, the head 10 being relatively large so that the same will not slip or move with respect to the article being lifted.

Forming a part of the jack is a hollow body portion 11 that extends laterally and as shown is provided with a tubular portion 12 formed with shoulders 13 to engage the upper edge of the members 6, over which the tubular portion 12 is positioned. The member 12 is formed with a slotted portion 63 through which the pawls designed to accomplish the lifting result operate.

The lifting bar is indicated at 14 and has one end thereof pivotally supported within the body portion at 15, the pawl 16 which cooperates with the teeth 9 of the lifting bar 8 being pivotally connected to the bar 14 at 17.

Pivotally mounted within the body 11 at 11' is a pawl 18 which also cooperates with the teeth 9 to hold the lifting bar 8; when the same has been raised by the pawl 16. The pawl 19 is also pivotally supported within the body 11 at 19' and is adapted to engage the teeth 7 of the member 6 to support the weight of the body 11 after the body 11 has been lifted by a stroke of the bar 14.

Mounted on the bar 14 is a relatively long pawl 20 that also engages the teeth 7 to lift the body portion upon a downward movement of the outer end of the bar 14. From the foregoing it will be obvious that upon the downward movement of the outer or free end of the bar 14, the pawl 16 contacting with the teeth 9 of the bar 8 will operate to lift the bar 8, and at the same time, the downward movement of bar 14 will cause pawl 20 to engage teeth 7 on member 6 and lift body portion 11.

Pivotally supported by the body portion 11 is a link member indicated at 21 to which link member is pivotally connected link members 22 and 23 respectively which carry link members 24 and 25 respectively at their outer or free ends. A spring member indicated at 26 connects the relatively long pawl 20 with the free end of the link member 24 while the spring member 27 connects the link member 19 with the link member 22 at a point adjacent to the pivot pin that connects the links 22 and 24.

The pawl 16 has connection with the link member 23 by means of the spring member 28, while the pawl 18 has connection 110

with the link member 25 by means of the spring member 29. As shown the link members 24 and 25 move between the ribs 25'. It is to be understood that the spring members are secured to the pawls so that when the pawls are moved in one direction, the spring members will be bowed and placed under tension to cause the pawls to move into close engagement with the teeth associated therewith. Connected with link member 21 and extending through slot 21' is a shaft 30 provided with a finger piece 31 at its outer end so that by moving the finger piece, the link member 21 may be adjusted to control the movements of the spring members.

The operation of the jack is as follows: Assuming that the jack has been positioned under an object to be raised, the lifting bar being in a position as illustrated by Figure 1 of the drawings. It will be obvious that upon a downstroke of the outer end of the bar 14, the pawl 16 will lift the bar 8, and when the bar 14 has been moved to the limit of its downward movement, and the forward end of the bar has been raised, the movement causes the link members 16 and 18 to move downwardly in a vertical plane to the end that the spring members 28 and 29 are bowed causing the pawls 18 and 16 to move into engagement with the teeth of the bar 8 to hold the bar 8 against downward movement. Upon the next stroke of the bar 14 the bar 8 will be again lifted, which operation is repeated until the bar 8 has reached the desired height.

If it is desired to release the jack and lower the object lifted thereby, it is only necessary to turn the finger piece 31 to a position as indicated by Figure 2 of the drawings, whereupon an upward movement

of the bar 14, or outer end thereof will result in the bar 8 being lowered, and when the bar 14 has reached the limit of this stroke it follows that the spring 29 is placed under tension and the pawl 18 is moved into engagement with the teeth of the bar 8 to hold the bar against further downward movement until the pawl 16 has again been moved to lift the teeth of bar 8 in the lowering operation.

While I have shown and described the operation of the uppermost pawl it is to be understood that the lower pawls of the jack construction operate in a manner identical with that described as the operation of the pawls 16 and 18.

I claim:

In a double lifting jack, a base, an upwardly extended tubular support having teeth formed thereon, a body portion having a hollow section fitted over the tubular support, a lifting post movable within the tubular support and having downwardly extending teeth, a lifting bar having one end thereof pivotally mounted within the body portion, pawls pivotally connected with the lifting bar and disposed on opposite sides of the support for the lifting bar, said pawls adapted to move the post and body portion vertically when the lifting bar is reciprocated, and supporting pawls cooperating with the teeth to prevent reverse movement of the post and body portion.

In testimony that I claim the foregoing as my own, I have hereto affixed my signature in the presence of two witnesses.

GEORGE STEELE.

Witnesses:

JOHN G. THOMPSON,
J. M. HALL.
